CLAIM

The ornamental design for a dual-axis swivel speaker mount, as shown and described.

DESCRIPTION

FIG. 1 is a front perspective view of a dual-axis swivel speaker mount according to the present design;

FIG. 2 is a front view of the dual-axis swivel speaker mount as shown in FIG. 1;

FIG. 3 is a rear view of the dual-axis swivel speaker mount as shown in FIG. 1;

FIG. 4 is a right side view of the dual-axis swivel speaker mount as shown in FIG. 1;

FIG. 5 is a left side view of the dual-axis swivel speaker mount as shown in FIG. 1;

FIG. 6 is a top view of the dual-axis swivel speaker mount as shown in FIG. 1;

FIG. 7 is a bottom view of the dual-axis swivel speaker mount as shown in FIG. 1; and,

FIG. 8 is a front perspective view of the dual-axis swivel speaker mount, shown in an alternate configuration.

The broken lines shown in FIGS. 1-8 are for purposes of illustrating portions of the dual-axis swivel speaker mount that form no part of the claimed design.
